JAMES C. MARIS AND HENRY K. HARWICK, OF PHILADELPHIA, PENNSYLVANIA.

STEAM-PIPE SUPPORT FOR ARTICULATED LOCOMOTIVES.

Application filed September 15, 1926. Serial No. 185,577.

Our invention relates to certain improvements in articulated locomotives of the "Mallet" type.

In this type of locomotive the steam pipe 5 leads from a distributor under the smoke-box, in the present instance, to the forward cylinder structure carried by the forward frame of the locomotive, the boiler being carried by the rear frame and overhangs 10 the forward frame.

The object of our invention is to provide means for returning the vertical section of the steam pipe to a central position after passing a curve, and to prevent the horizontal section from turning.

In the accompanying drawing:

Fig. 1 is a diagrammatic view of a "Mallet" locomotive showing the location of the forward steam pipe; 20 Fig. 2 is a side view of the steam pipe, the distributor being shown in section on the line 2—2, Fig. 3; and Fig. 3 is a sectional view on the line 3—3, Fig. 2.

1 is the forward frame of the articulated locomotive and 2 is the rear frame pivotally connected to the forward frame. The boiler 3 is rigidly mounted on the rear frame and overhangs the forward frame. The cylinder structure 4 is mounted at the forward end of the rear frame and the cylinder structure 5 is mounted at the forward end of the forward frame. Under the smoke-box 6 of the boiler is a steam distributor 7 which receives steam from the superheater and distributes it to the forward cylinders through a jointed pipe 8 and to the rear cylinders through pipes 9.

The pipe 8 has a vertical section 10 and a horizontal section 11. At the upper end of the vertical section 10 is a ball 12 adapted to a socket 13 in an extension 14 of the distributor 7. The socket is made in sections and is held in place by a follower 15. This joint allows the vertical section 10 of the pipe to swing laterally when the locomotive is passing around a curve, and the front frame swings out from under the boiler.

At the lower end of the vertical section 10 of the pipe is a ball 16, and in the upturned end of the horizontal section 11 is a socket 17 similar in construction to the socket 13. At the outer end of the horizontal pipe is a ball 18 mounted in a socket 19 formed in the fitting 20 which is connected to the cylinder structure 5.

When the forward frame moves laterally from under the boiler, the sections of the pipe swing on their ball joint and in many cases the pipe remains at one side of the center. The main object of our invention is to provide means for returning the pipe to its central position as soon as the locomotive passes over a curve and is on a straight track.

Depending from the underside of the distributor 7 at each side of the center are a pair of brackets 21. A bar 22 is secured to each pair of brackets as shown, and on each bar is an eye-bolt 23, located forwardly of the center line X through the vertical section 10 of the pipe.

On each side of the upturned end of the horizontal section 11 is a bracket 24 in which is an eye-bolt 25.

Spring 26—26 extend diagonally from the eye-bolts 23 to the eye-bolts 25, and yieldingly retain the pipe in a central position, but allow the pipe to move to accommodate the movement of the front frame 1 and boiler 3.

The springs also prevent the horizontal section of the pipe from turning, and they aid in supporting the rear end of the horizontal pipe and relieve the ball and socket joints from a certain amount of strain.

When the locomotive is passing around a curve, the front frame takes the curve first and swings laterally from under the boiler. The jointed pipe connection between the boiler and the cylinder structure on the front frame accommodates itself to this movement, the spring on one side yielding. When the locomotive is on a straight piece of track, the springs return the steam pipe to its normal central position and yieldingly hold the pipe in this position.

We claim:

1. The combination in an articulated locomotive in which the boiler overhangs the front frame, of a flexible steam supply pipe connected at one end to a distributor on the boiler, and at the other end to the forward cylinder structure, with supporting springs, one located on each side of the pipe, and arranged diagonally at the upper ends of the pipe, the upper ends of the springs being attached to the boiler structure.

2. The combination in an articulated locomotive, in which the boiler overhangs the front frame thereof, of a front cylinder structure; a steam distributor on the boiler;

and a steam supply pipe leading from the distributor to the cylinder, said pipe having a horizontal section and a vertical section connected by flexible joints with springs, one located on one side of the pipe and the other located on the opposite side thereof, one end of each spring being attached to the inner end of the horizontal pipe and the upper end being attached to the distributor.

3. The combination in an articulated locomotive with a front and rear frame; a boiler mounted on the rear frame and extending over the front frame; a cylinder structure mounted on the front frame; a distributor located under the smoke-box of the boiler, the steam supply pipe leading

from the center of the distributor to the cylinder structure, said pipe consisting of a horizontal section and a vertical section; ball joints connecting the sections of the pipe; flexible joints on the distributor and the cylinder structure; a bracket at each side of the inner end of the horizontal section of the pipe; brackets depending from the distributor and bars secured to the brackets; eye-bolts attached to the bar and to the brackets on the pipe; and coiled springs connecting the eye-bolts, the springs being arranged at an angle so as to return the pipe to its central normal position.

JAMES C. MARIS.
